UNITED STATES PATENT OFFICE.

FRANK T. FEICHT, OF CANTON, OHIO.

SASH-LOCK.

1,140,027.

Specification of Letters Patent. Patented May 18, 1915.

Application filed September 18, 1913. Serial No. 790,493.

To all whom it may concern:

Be it known that I, FRANK T. FEICHT, a citizen of the United States, residing at Canton, in the county of Stark, State of Ohio, have invented certain new and useful Improvements in Sash-Locks; and I do hereby declare the following to be a full, clear, and exact description of the invention, such as will enable others skilled in the art 10 to which it appertains to make and use the same.

This invention relates to sash locks.

The object of the invention resides in the provision of a sash lock which will effectively prevent the opening of the sashes of a window from the exterior when said sashes are in closed position or one or both partly opened for ventilating purposes.

A further object of the invention resides 20 in the provision of a sash lock which cannot be surreptitiously operated to released position from the exterior of the window, but which can be readily released from the interior to permit raising and lowering of the 25 sashes at will.

With the above and other objects in view the invention consists in the details of construction and in the arrangement and combination of parts to be hereinafter more fully 30 described and particularly pointed out in the appended claim.

In describing the invention in detail reference will be had to the accompanying drawings wherein like characters of reference 35 denote corresponding parts in the several views, and in which—

Figure 1 is a view in elevation of a window having a pair of the improved sash locks associated therewith; Fig. 2, a section 40 on the line 2—2 of Fig. 1 on an enlarged scale; Fig. 3, a section on the line 3—3 of Fig. 1; and Fig. 4, a detail perspective view of the improved lock detached.

Referring to the drawing the lock is 45 shown as comprising a securing plate 10 to one end of which is hingedly connected a frame engaging plate 11 having a central recess 12 in its free edge, the remaining portion of the free edge of the plate 11 being 50 serrated as at 13. The plate 11 has formed thereon a finger grip 14 for a purpose that will presently appear. The improved lock

further embodies a plate 15 secured on the plate 10 at right angles to the latter and having hinged to one edge thereof an engaging plate or pawl 16 which also has formed thereon a finger grip 17. The upper and lower window sashes are indicated respectively at 18 and 19, while the window frame in which said sashes slide is indicated 60 at 20. In applying the lock the plate 10 is secured to the top of the lower sash 19 in such position that the free end of the plate 11 will pass into and engage the inner wall of the sash groove of the frame 20, the sash cord being disposed in the recess 12. With the plate 10 thus mounted it will be apparent that the pawl 16 will be disposed in position to engage the teeth 21 of a rack bar 22 secured to the upper sash 18. When the 70 plate 11 is in engagement with the frame 20 and the pawl 16 in engagement with the teeth 21 it will be apparent that the upper sash 18 cannot be lowered nor the lower sash 19 be raised, the plate 11 and pawl 16 together with the rack bar 22 serving as a 75 double lock to prevent such movement of the sashes. It will be obvious that by swinging the plate 11 away from the frame 20 to its limit and the pawl 16 away from the 80 rack bar 22 the sashes may be adjusted as desired and the lock again set.

What is claimed is:—

The combination with a window frame and upper and lower sashes slidably mounted therein, of a toothed rack secured against the inner side of the upper sash adjacent the lower end thereof, a plate secured to the top of the lower sash, an arm hinged to one end of said plate and having its free end provided with a recess and with teeth and adapted for engagement with the window frame, said recess being adapted to receive a sash cord, a second plate mounted on the first named plate transversely of the latter, and an arm hinged to one end of the second plate and engageable with said rack. 90

In testimony whereof, I affix my signature in the presence of two witnesses.

FRANK T. FEICHT.
